BACTERIOSTAT

Marjorie E. Moreland, Summit, and Daniel H. Reheis,
Maplewood, N.J.

No Drawing. Application May 3, 1956
Serial No. 582,321

1 Claim. (Cl. 167—14)

This invention relates to bacteriostasis.

The bacteriostatic agent is an aluminum chlorhydroxy complex of the type formula $Al_x(OH)_yCl_z$, in which x is an integer and y and z are numbers whose sum is $3x$. A particularly satisfactory product for the present purpose has the empirical formula $Al_2(OH)_5Cl$.

Such material has been used heretofore as an astringent. We have now discovered that the complex, when used in aqueous solutions so dilute as to be ineffective as astringents, is effective as a bactericide or bacteriostat.

Briefly stated, the invention comprises an agent in the form of very dilute aqueous solutions of an aluminum chlorhydroxy complex for inhibiting the growth of micro-organisms and also the process of contacting the micro-organisms with the complex of such dilutions. In the most satisfactory embodiment, the invention comprises the complex as a bacteriostat at dilutions corresponding to approximately 10^4 — 2.5×10^5 parts of water for 1 of the aluminum chlorhydroxy complex on the dry basis. At higher concentrations, the complex kills much smaller numbers of bacilli per unit of complex used.

We have found a peak in the effectiveness at such extreme dilutions. Tests were made, for example, as follows: To each of five dilutions of aluminum chlorhydroxy complex 1 ml. of the micrococci bacterial suspension containing a known number of organisms, ordinarily from 500,000—1,200,000 per ml. was mixed with the said complex at room temperature and allowed to stand for selected periods of time. 1 ml. was then transferred from each dilution to a petri dish and 10 ml. Difco Bacto-Tryptose agar was added. Plates were allowed to solidify and then placed in a 37° C. incubator for 48 hours. The petri dish was then examined with a Quebec colony counter and the number of colonies determined in accordance with usual technique, the number of colonies counted showing the number of bacteria remaining viable after contact with the complex. The counts given herein are for the most part averages of two or more tests for each dilution of the complex.

Parts of water, approx., for 1 part of dry aluminum chlorhydroxy complex ¹	pH of solution		Number of colonies after incubation
	Complex	Complex +broth	
$10^2=100$	4.47	5.37	35.
$10^3=1,000$	5.35	7.08	259.
$10^4=10,000$	6.03	7.08	23.
$10^5=100,000$	6.18	7.08	10.
$2.5 \times 10^5=250,000$	142.		
$5 \times 10^5=500,000$	TNTC (too numerous to count).		
$10^6=1,000,000$	TNTC.		

¹ The number of parts of water used were actually about 90% of those shown in all dilutions stated here and elsewhere herein. Thus the figure 10,000 stated exactly should be 9,000. The figures are rounded as shown, however, to avoid the impression of an accuracy of degree that does not prevail in bacteriological work of this kind.

2

The complex used in obtaining the data tabulated above contained 1.5 Al for 1 Cl.

Proportions are expressed as parts by weight in all cases unless specifically stated to the contrary.

As to materials used, the aluminum chlorhydroxy complex used is a commercial grade of high purity such as made by the interaction of aluminum powder with aluminum chloride, as described in Patent 2,196,016, issued to Huehn et al., on April 2, 1940. The aluminum powder and the chloride are proportioned to give the ratio Al:Cl desired in the finished complex.

When the proportion of aluminum in the complex is less than 1.5 atoms for 1 of chlorine, there is a decided loss of bacteriostatic effect. When the proportion is 15 more than 2.5:1, the complex is difficult to make and to use. The aluminum chlorhydroxy complex at high concentrations, as above 1 part for 100 of water has a tendency to precipitate proteins, as shown by its effect on the agar composition used for test purposes 20 by us.

The complex improves in effectiveness with age, as from 2 weeks to 2 months, the effect of age as well as promoters being illustrated in Example 3.

The bacteria to be contacted with the solution of the 25 complex may be either gram positive, such Micrococcus, or gram negative, such as Escherichia and Aerobacter.

The water used in all tests reported herein was soft (substantially free from the ions of hard water, i.e. calcium, magnesium, sodium, sulfate, chloride, and bicarbonate ions) and, more specifically, was distilled water unless specifically stated to the contrary. The pH of freshly made solutions of the chlorhydroxy complex, at all dilutions up to the 1:10⁶ ran below 6.5.

Cultures held 3, 9, and 14 minutes in contact with the complex at high dilution before mixing with the agar in a petri dish showed that the bacteriostasis increases with time. The major part of the effect, however, comes in the first 3 minutes. In the test tabulated above, for instance, the results for various periods with the dilution 10⁵ parts of water for 1 of the complex, for various periods of contact before incubation and with an original population of 1,000,000 organisms per ml., are as follows:

Minutes after inoculation with micrococci	Remaining viable bac- teria as shown by colonies after incu- bation at 38° C. for 48 hrs.
3	23
9	5
14	2

55 The exact temperature of mixing the bacterial suspension and the chlorhydroxy complex is relatively unimportant. In tests of mixing at 28°, 35°, and 45° C., the results after incubation have been found to be approximately the same.

60 The invention will be further illustrated by description in connection with the following specific examples of the practice of it.

EXAMPLE 1

An aluminum chlorhydroxy complex containing 2 atoms of aluminum for each atom of chlorine and containing iron in proportion less than 50 parts for a mil-

lion of the complex, is dissolved in water in amount to correspond to 20 parts on the dry basis for 80 of water.

The solution so made is ready for dilution and subsequent use as a bacteriostat.

EXAMPLE 2

An aluminum chlorhydroxy complex, as taken for dilution, contained 46% of solids including aluminum, calculated as Al_2O_3 21.8% and as Al 11.53%, and chlorine calculated as Cl 10.1%. These percentages correspond to an atomic ratio of ca. 1.5 Al for 1 Cl. This complex was tested bacteriologically by the method described above.

The most effective dilution, from the standpoint of bacteriostatic effect, was approximately 100,000 parts of water for 1 of the complex on the dry basis.

EXAMPLE 3

This example illustrates the use of promoter additives with the aluminum chlorhydroxy complex.

Glycerine is particularly effective as the additive. Other non-toxic polyhydric alcohols that illustrate the class of satisfactory materials are propylene glycol and sorbitol.

Another class of additives that are satisfactory are non-toxic surface active agents. Examples are the non-ionics such as polyalkylene oxide derivatives of the partial esters of sorbitan, sorbitol, and glycerine with the higher C_{12} - C_{18} fatty acids such as lauric, oleic, and stearic. The number of alkylene oxide groups introduced into the partial ester (mono- or di-) may vary over a considerable range, as for instance from 1-100 and is suitably 5-25. The alkylene oxide ordinarily is ethylene oxide, although the propylene and isopropylene oxides may be used. Commercial products of this kind that we may use are those known as Span and as Tween. Other surface active agents that may be used are glycerine and ethylene glycol, both in the form of monoesters with the higher fatty acids listed above.

The chlorhydroxy complex containing the additives were tested for bacteriostatic effect with essentially the same technique as described earlier herein.

In these particular tests, the mixture of the bacterial suspension with the chlorhydroxy complex, additive, and water was held for 3 minutes after mixing before the agar was introduced. The incubation that followed was at 37° C. for a period of 48 hours.

Most of the numerical counts of colonies tabulated below are averages of several runs made on different days.

The counts of the colonies after incubation were compared, for each additive and complex, with a control in which the chlorhydroxy complex was omitted.

The proportion of the additive was 25 parts by weight in every instance for 100 of the aluminum chlorhydroxy complex on the dry basis.

In all cases, the aluminum chlorhydroxy complex contained aluminum in the proportion of 2 atoms for 1 atom of chlorine. The complex was of two grades, referred to below as "regular" and "special," respectively. The regular was freshly made by reaction of aluminum powder and aluminum chloride, as described earlier herein, and was filtered. The special was made similarly except that the filtrate (containing the said complex) was vacuum dried to a content of 47% of aluminum calculated as Al_2O_3 . The dried material was then dissolved promptly in water and kept in solution at ambient temperatures for 68 days before use in the test with glycerine additive and for 77 days before test with the additive Tween.

The tables that follow show the dilutions at which the bacteriostatic compositions were tested and the count of colonies after incubation. In some of these runs there was a variation in the bacterial count from a finite number to numbers too numerous to count (TNTC). When this variation was found, it is so indicated in the table.

Glycerine plus chlorhydroxy complex

5	Parts of water for 1 part of mixed glycerine and complex, dry basis	Count after incubation		
		Regular complex	Special complex	Control, glycerine with no complex
10 ²	TNTC	1866-TNTC	0	TNTC.
10 ³	188-TNTC	0	0	TNTC.
10 ⁴	36-TNTC	0	0	TNTC.
10 ⁵	68-TNTC	0	0	TNTC.
10 ⁶	832-TNTC	362	0	TNTC.

It will be seen, by comparing the data above with that earlier herein, that the glycerine additive is a promoter of the bactericidal or bacteriostatic effect.

The additive used in obtaining the following data was polyethylene oxide derivative of sorbitan monolaurate (Tween).

Tween plus chlorhydroxy complex

20	Parts of water for 1 part of mixed glycerine and complex, dry basis	Count after incubation	
		Special complex	Control (Tween) with no complex
10 ²	TNTC	0	TNTC.
10 ³	41-TNTC	0	TNTC.
10 ⁴	29	0	TNTC.
10 ⁵	6	0	TNTC.
10 ⁶	241-TNTC	0	TNTC.

Various proportions of the additive promoter may be used as for instance 1%-10% of the weight of the aluminum chlorhydroxy complex. Proportions substantially below 1% are ineffective and those above 10% are unnecessary, and, therefore, uneconomical.

The tests of this Example 3 show that the aged (special) complex was more effective than the regular.

Another promoter that may be and suitably is admixed with the aluminum chlorhydroxy complex is an alkali metal iodate such as sodium or potassium iodate. Thus, we have used potassium and sodium iodates. The proportion recommended is 2-15 parts for 100 parts of aluminum chlorhydroxy complex on the dry basis, best results having been obtained when the proportion of the iodate is not above 5 parts of the iodate for 100 parts of the complex.

A feature of the use of iodates with the complex is the killing at very great dilutions. In a representative run, using 5 parts of the potassium iodate for 100 of the aluminum chlorhydroxy complex and the techniques described earlier herein, we have found the following counts of Micrococcii for the various dilutions of the complex and iodate mixture:

50	Parts of water for 1 of aluminum hydroxy complex mixed with 0.05 part of KIO_3	Count after incubation
10 ²	0	TNTC
10 ³	123	0
10 ⁴	15	0
10 ⁵	0	0
10 ⁶	800	0

The results, here as elsewhere, vary somewhat in work of this kind with the time of contact of the bacteriostat with the Micrococcii, the age of the complex at the time of mixing with the bacteria, and to a lesser degree between various runs under conditions intended to be the same. The data given, however, are illustrative of the high killing obtained at dilutions around 100,000 parts of water to 1 part of complex.

In other tests, in which the complex and iodate mixture had stood for 5 days, before being mixed with the bacteria, there was complete killing at 3 minutes, 9

minutes, and 14 minutes with all dilutions from 100 parts of water to 1,000,000.

EXAMPLE 4

Other additives that may be mixed with aluminum chlorhydroxy complex before contact with the bacteria are the following: Phospholipids of which the lecithins, cephalins, and sphingomyelins are examples, reducing agents such as soluble bisulfites and dithionates of which the sodium salts are satisfactory and the most economical; oxidizing agents of which examples other than the iodates are the chromates and manganates such as sodium or potassium chromate and potassium permanganate; and surface active agents other than those described above, such as anionics including the sodium or potassium alkyl aryl sulfonates, lauryl sulfonate, and alkyl sulfates.

EXAMPLE 5

When the water of original make-up and dilution, used in the tests reported earlier herein including Examples 1-4, was replaced by hard water, there was a sharp decrease in the effectiveness of the bacteriostat at the relatively high dilutions.

The following data shows the comparative effectiveness of the aluminum chlorhydroxy complex for distilled water and in this hard water, the bacteria used being *Micrococcus*.

Parts of water for 1 part of aluminum chlorhydroxy complex	Count after incubation	
	Distilled water	Hard water
10 ²	TNTC	TNTC
10 ³	40	0
10 ⁴	50	TNTC
10 ⁵	5	TNTC
10 ⁶	100	TNTC

While various explanations may be advanced to explain these results with the hard water, it is considered that an important part of the effect may be the decomposition or change of structure of the aluminum chlorhydroxy complex by ions in the hard water, the ion content as a whole causing the pH to be above 7 and consisting principally of calcium, magnesium, sodium bicarbonate, sulfate, and chloride.

The hard water used in the tests of this example was the city water supply of Summit, New Jersey, of pH about 7.25 and the following approximate analysis, the Ca, Mg, Cl, and Na being reported as the elements.

Determination:

	P.p.m.	50
Alkalinity, total	106	
Hardness, permanent	32	
Hardness, total	138	
Carbonic acid, free	2.6	

Total solids	225
Iron and aluminum, calc. as oxides	0.7
Calcium	29.9
Magnesium	7.9
Chloride	9.0
Sodium	14.9
Nitrites	0.001
Nitrates	0.7

EXAMPLE 6

The procedure of Examples 1-3 is followed except that the fungi *Trichophyton interdigitale* was the organism to which the dilute solution of the complex was applied.

EXAMPLE 7

The procedure of Examples 1 or 3 is followed except that the proportion of water is decreased to $10^2 \times$ the amount of the aluminum chlorhydroxy complex on the dry weight basis. With the distilled or soft water, even higher concentrations, as up to 1 part of the complex to 5 parts of water, are satisfactory but unnecessary.

It is to be understood that it is intended to cover all changes and modifications of the examples of the invention herein chosen for the purpose of illustration which do not constitute departures from the spirit and scope of the invention. It is to be understood also that the aluminum chlorhydroxy complex is not only a bacteriostat but also a bactericide.

What is claimed is:

The process of inhibiting the growth of bacteria which comprises applying to the bacteria and maintaining in contact therewith for a period of at least three minutes a bacteriostat consisting essentially of an aqueous solution of aluminum chlorhydroxy complex of the empirical type formula $Al_x(OH)_yCl_z$, in which x is a number within the range about 1.5-2.5, z is 1, and the sum of y and z is $3x$, the solution being in the condition of having been aged at ambient temperatures for at least 2 weeks and the concentration of the said complex at the time of application to the bacteria being about 1 part for 10^4 to 2.5×10^5 parts of water.
